JEREMIAH STEVER AND J. A. WAY, OF BRISTOL, CONNECTICUT, ASSIGNORS
TO JOHN H. SESSIONS, OF THE SAME PLACE.

Letters Patent No. 61,111, dated January 8, 1867.

IMPROVEMENT IN WOOD LATHES FOR TURNING KNOBS.

The Schedule referred to in these Letters Patent and making part of the same.

TO ALL WHOM IT MAY CONCERN:

Be it known that we, JEREMIAH STEVER and JOHN A. WAY, of Bristol, county of Hartford, and State of Connecticut, have invented a certain new and useful Improvement in Machines for Manufacturing Furniture Knobs, &c.; and to enable others skilled in the art to make and use the same, we will proceed to describe, by referring to the drawings, in which the same letters indicate like parts in each of the figures.

The nature of this invention consists, or rather it will be understood, from the specification and drawings, the object of which is to greatly facilitate the manufacture, produce uniformity of shape and proportion, and thereby produce a cheaper and better article. In the accompanying drawings—

Figure 1 is a front elevation.

Figure 2 is a right-hand end elevation.

Figure 3 is a left-hand end elevation.

Figure 4 is a back side elevation.

Figure 5 is a top or plan view.

A is the framework to or upon which the mechanism is arranged. B¹ is the driving-shaft, having a pulley, a, to which the power is applied, by means of a belt, to give impetus to the machine. B² is a cam-shaft which receives its motion from (indirectly) the pulley b, on the driving-shaft B¹, through the stud or loose pulley e, which has a pinion gear, d, secured thereto, which works into the large gear d', upon the outer end of the shaft B². C is a skeleton cylinder secured upon the front end of the shaft B². D are spindles, having sockets in the front ends thereof, for the reception of proper dogs or holders for holding the blank or block from which the knob is to be made by the machine; these spindles are made much in the usual way of making lathe spindles, &c. These spindles are arranged in bearings formed in the rim of the cylinder C, having pulleys, E, of about uniform size; these spindles are operated alternately by a belt, or its equivalent, which passes over the pulleys E from the pulley F, which is secured on one end of the driving-shaft B¹. G is a bracket, made in the form of a segment of a circle, and a little larger than the diameter of the cylinder C, which is firmly secured to the framework A, and otherwise of such shape and proportion as to secure strength and firmness thereto during the operation of the machine. Upon the face of this bracket, G, are arranged studs, H, ^{1 2 3 4 5}, the faces of which are of about equal or corresponding distances from each other, and with the centres of the spindles D in or upon the face of these studs, H, are arranged the tool-stocks I, the object of which is to hold properly-formed or shaped tools for cutting or forming the blank or block into the required shape knob, which (the tool) is secured thereon in any of the common ways. These stocks are actuated back and forth, up to the blank, successively or simultaneously, as may be desirable, by the action of the cams J, or their equivalent, arranged upon the back side of the bracket G, by proper guide-ways, so as to secure a firm and easy motion thereof, and so as to be actuated by any proper mechanism arranged to produce a corresponding motion thereof with the cylinder C. L is an arm extending from the framework outward in front of the ends of the spindles D, upon which is arranged a presser-bar, a, the object of which is to press the blank firmly upon the dogs or holders, which are fitted into the sockets of the spindles D, and is operated by a blow against the outer end thereof, (the bar a,) or by means of a hand-lever, b. M is a clearer clutch, secured upon the outer end of the spindle N, having its bearings in the framework A, so as to allow of both a lateral and vibratory motion thereof. The object of this clutch is to remove the knob, by an independent self-acting motion of the clutch M, from the spindle dog, by receiving it (the dog) between its prongs, while the prongs themselves pass (as the cylinder or spindles move from one resting point to another) between the ends of the spindles D and the finished knob, when by the joint action of the lever O and cam P, or their equivalents, upon the spindle N, will remove the knob from the dog, in readiness to receive another block. On the back end of the shaft B³ is secured a notch-wheel, Q, having the same number of notches or depressions in the edge thereof as there are spindles in the wheel C. R is a ratchet-bar. R² is a lock-bar, which throws the bolt S into or draws it out of the notches in the wheel Q; these bars or shafts, R and R², are operated to perform their proper functions by means of the cam T¹. U¹ is a lever which moves the trimming stock I², and is actuated by the cam T². U³ is a lever which operates, through its proper connections, the segment cam-plate K, and is actuated by the cam T⁴.

Now, in putting this machine in operation, take a block, cut the proper size, first having a hole made therein to receive the dog or holder which is fitted to the sockets of the spindles D, place it upon the dog just back of the presser L, and by the aid thereof (the presser) force it firmly on to the dog, one after the other, as often as the movement of the cylinder, and as the block, by the action or motion of the cylinder, comes against the tool-stock, the tool thereon is compressed to do its appointed work, or its portion of the work; thence forward to the next tool, successively, until the knob is completed and thrown from the dog, by the uniform and repeated action of the respective parts, as above described. Each spindle, while rapidly revolving with its block, is brought directly to the action of the tools arranged upon the tool-stocks I, ^{1 2 3}, &c., so that each may perform its respective portion of the work nearly at the same instant of time. And as the spindle holding the finished knob moves along near to the clutch, the clutch M will enter astride of the dog, between the end of the spindle D and the knob, and by the joint action of the lever O and cam P, the spindle N, with the clutch M, will be thrust forward, and the knob removed from the dog thereby. This operation will be repeated sixteen times (more or less, according to the number of spindles, D, used in a machine) during each revolution of the cylinder C. It will be particularly noticeable that the device which operates the cutting tools is designed to move or to actuate the stocks I towards the spindles D, at or nearly at the same instant of time, and also between each periodical movement of the cylinder, during each revolution.

We believe we have thus shown the nature, construction, and operation, so as to enable others skilled to make and use the same therefrom.

What we claim, therefore, and desire to secure by Letters Patent, is—

1. We claim the cylinder C, in combination with the notch-wheel Q, ratchet-bar R, lock-bar R², bolt S, and actuating pin-cam T¹, for the purpose of giving a periodical movement to said cylinder C, substantially as described.
2. We claim the tool-stocks I, ^{2 3 4 5 6} 7, in combination with the cams J, arranged upon the plate K, lever U³, with its connecting arms actuated by the cam T⁴, substantially as and for the purpose described.
3. We claim the clearer clutch M, in combination with the lever O, and cam P, vibrating spindle N, substantially as and for the purpose described.
4. We claim organizing in one machine the above enumcrated successive operations for turning, finishing, and clearing the knobs from the machine as described, when arranged and operating substantially as set forth.

JEREMIAH STEVER, [L. S.]

JOHN A. WAY. [L. S.]
